UNITED STATES PATENT OFFICE.

RALPH S. SHERWIN, OF EAST ST. LOUIS, ILLINOIS, ASSIGNOR TO ALUMINUM COMPANY OF AMERICA, OF PITTSBURGH, PENNSYLVANIA, A CORPORATION OF PENNSYLVANIA.

PRODUCTION OF HYDROFLUORIC ACID AND SALTS THEREOF.

1,301,325.

Specification of Letters Patent.

Patented Apr. 22, 1919.

Application filed July 28, 1915. Serial No. 42,291.

To all whom it may concern:

Be it known that I, RALPH S. SHERWIN, a citizen of the United States, residing at East St. Louis, in the county of St. Clair and

5 State of Illinois, have invented certain new and useful Improvements in the Production of Hydrofluoric Acid and Salts Thereof, of which the following is a full, clear, and exact description.

10 The invention which forms the subject of my present application relates to the production of hydrofluoric acid and salts thereof, particularly sodium or other alkaline fluorides, and its chief object is to provide a continuous and economical process for the purpose. Another object is to provide a process which can be performed without injury or inconvenience to the attendant workmen by exposure to acid fumes. To these and other 15 ends the invention consists in the novel process and steps hereinafter described.

In practising my improved method or process I employ preferably a still of the type described in the copending application 25 of Edwin S. Fickes, Ser. No. 828,436, and a condensing or absorbing system of the kind described in my prior application Ser. No. 1,964. These devices are illustrated in the accompanying drawings, in which—

30 Figure 1 shows the Fickes still in longitudinal section.

Fig. 2 is a plan view of the still, with the furnace setting or flue in horizontal section.

Fig. 3 is a cross section of the still on line 35 3—3 of Fig. 1.

Fig. 4 is a cross section, on a slightly larger scale, of the retort alone, showing the rotary agitator for stirring the non-gaseous contents.

40 Fig. 5 is a detail view of the retort in elevation, showing means for cooling the shaft of the agitator.

Fig. 6 is a view, partly in side elevation but partly in vertical longitudinal section, 45 of the condensing or absorbing apparatus.

The still illustrated consists, in general, of a long, tubular, stationary retort 10, inclosed in a suitable housing or setting 11, by which a gaseous heating medium is passed along the retort, which medium may be the hot products of combustion from a furnace or fire chamber 12. Vertical baffles 13, extending alternately from opposite sides of the setting cause the smoke and gases to take 50 a more or less tortuous course, thereby giv-

ing a more efficient utilization of the heat. At the end opposite the fire chamber the products of combustion flow downwardly and laterally through a flue 14 to the stack, shown in horizontal section at 15, Fig. 2. 60

In the present instance, the retort 10, preferably inclined downward toward the fire chamber, for example at an angle giving about a half-inch fall per foot of length, is formed of cast iron pipe-sections, the straight 65 sections alternating with the T sections. The latter are turned up, and are provided with suitable closures, as 16, removably secured by any convenient means not shown. These lids or closures 16 may also be used 70 to support hangers 16^a for the shaft of the agitator, described hereinafter. The closure 17^a on the T 17 at the upper end of the retort, is provided with means for supplying the necessary acid producing materials, continuously or intermittently. In the drawing I have shown a simple hopper 18, with a gate valve 19, by which convenient quantities of material can be delivered into the retort at proper intervals. The closure 17^a 80 also has an outlet pipe 20 to carry off the hydrofluoric acid vapor and conduct the same to a suitable condenser, for example that shown in Fig. 6. The pipe, which is preferably made of lead or lined with lead, is provided with a valve 21 to regulate the rate of outflow. 85

At its lower end the retort terminates in a cross 22, having at the top a removable closure 23 and at the bottom a pipe 24 extending below the surface of the water in the pit 33, forming a water-seal. Journaled in the end closures 25, 26, is a shaft 27 extending through the retort at the axis thereof and provided with helically arranged radial 90 arms 28 equipped at their ends with paddles or scrapers 29 close to, but preferably not touching, the walls of the retort. At the lower end the shaft is connected with suitable driving mechanism, as for example an 100 electric motor 30, by means of a worm 31 and worm gear 32.

Fluorspar and sulfuric acid, mixed in suitable proportions, are fed into the hot still or retort at the upper end through the 105 hopper 18. In the retort it is thoroughly mixed by the revolving paddles 29, and gradually stiffens as it moves slowly down into the hotter parts. Finally it breaks up, part into powder and part into small balls or 110

rounded lumps. Meanwhile, the reaction between the calcium fluorid and the sulfuric acid goes on, yielding hydrofluoric acid (hydrogen fluorid, HF) in the form of vapor, 5 and calcium sulfate (CaSO_4) as a solid residue. The former goes off through the lead pipe 20; while the residue, as fast as it reaches the cross 22, falls into the pit 33 and is removed from time to time in any convenient way. If necessary to push the residue out, the lid 23 may be removed for the purpose.

The proportions of calcium fluorid and sulfuric acid may vary widely in practice. 15 Theoretically they should be in the proportion of 98 parts sulfuric acid to 78 parts calcium fluorid; but as natural calcium fluorid (fluorspar) is always impure and sulfuric acid varies in strength, such proportions 20 would involve more or less waste of the acid or fluorspar as any excess of the latter would remain in the residue and any excess of the former as a part of the latter would simply volatilize or remain in the residue. More 25 definite proportions cannot be given, since different lots of fluorspar and acid vary greatly, but the most economical proportions can easily be determined by analysis or trial or by both.

30 The temperature inside the retort or still at the hottest parts should not be less than about 315° C. (600° F.), but may be increased to any degree which will not injure the retort or soften the agitator shaft so 35 as to cause it to twist, bend, or spring. To prevent overheating of the shaft and permit higher temperatures to be used, the shaft may be hollow, as in Fig. 5, to carry water or other cooling medium supplied to the 40 lower end by a pipe 34 and discharged at the upper end by a pipe 35. The couplings 36 are of any suitable kind, permitting the shaft to turn. This shaft should, in most cases, revolve quite slowly. In a retort three 45 feet in diameter and about sixty feet long the shaft should require rather more than a minute to make one revolution, and the material should require not less than about three hours (better four) to pass from the 50 inlet to the outlet end. If the rate of progress is too fast the mixture is heated too rapidly and causes volatilization of the sulfuric acid, thus causing a loss of fluorin and giving a considerable amount of sulfuric 55 acid in the hydrofluoric acid condensed. If the retort is inclined, with the inlet for the fluorspar and sulfuric acid at the higher end, the paddles or scrapers 29 may be parallel to the axis of the retort, as the inclination of the latter, together with the agitation produced by the paddles, will cause the material to move through the retort at a fast enough rate.

In connection with the still above described, two condensing or absorbing cham-

bers A, B, Fig. 6, are employed, one designated the primary and the other the secondary condenser or absorber. Each is in the form of a box made of suitable material, for example the first of lead and the other of 70 wood, or both lead or both wood, elongated vertically and provided with baffles C, D, those in the primary absorber, and if desired those in the other also, being spaced successively farther apart from the top downward. The acid vapors and any other gas or gases mixed therewith enter the primary absorber A at the bottom through a conduit E which is connected with or is a continuation of the gas-outlet pipe 20 of the still 80 shown in Fig. 1. At the top of the absorber A is a water-inlet F, provided with a regulating valve F'. Entering from the conduit E the gases rise and encounter the water flowing over the baffles, which are preferably spaced closer together at the top to compensate for the rapid absorption of the gases and vapors by the water. At the bottom of the absorber A is an outlet G for the acid, discharging through a water seal 90 H. The unabsorbed or undissolved vapors and other gases leave the primary absorber A at the top and are conveyed by a conduit I to the lower part of the secondary absorber B, which has at the top a liquid inlet J provided with a valve J'. Water may be delivered by the latter if desired, but I prefer to employ an alkaline solution, as will be described hereinafter.

In the manufacture of aluminum fluorid, 100 or cryolite, and other fluorids, it is desirable to have the acid of sufficient strength, or of sufficiently high temperature, to cause it to react readily with the alumina or other base of the material used. Since the absorption of 105 hydrofluoric-acid vapors in water liberates a considerable amount of heat, I am able to obtain the hydrofluoric acid solution at any desired temperature by properly regulating the supply or temperature, or both, of 110 water to the absorber. By this means, both the sensible heat of the gases and vapors entering the absorber and the heat liberated by the condensation or absorption are utilized for the purpose of bringing the acid 115 solution to any desired temperature. Here the height of the absorber, and the number and spacing of the baffles (successively farther apart from the top downwardly), play an important part, in that by suitable proportioning of these features the absorption with a small quantity of water is increased, thereby giving not only a stronger solution but also giving the solution a higher temperature, thus increasing the efficiency of the 120 solution in the subsequent production of fluorids. By increasing the number of baffles and decreasing the amount of liquid entering at the top the strength of the acid solution 125 in the lower part of the absorber can be 130

carried to a high degree of concentration. This is due in part to the increased absorption of the acid vapors, and in part to the evaporation of the water in the absorber.

5 If the temperature rise is sufficient to cause the acid solution descending in the lower part of the absorber to boil (under the reduced pressure in the absorber) the evaporation will be more rapid, and the concentration 10 within certain limits, will be greater. A boiling solution of hydrofluoric acid in water may give off both hydrofluoric acid and water vapor, but the vapor is greatly in excess until the acid solution reaches a 15 concentration of about 30 per cent. The evaporation by boiling of the descending stream in the lower part of the condenser has the advantage of removing the excess heat from the liquid, so that it is capable 20 of absorbing more acid from the strong acid vapors entering at the bottom. The water vapor formed in the lower part of the absorber may be condensed in the upper part by the incoming liquid, or part of it may 25 pass into the secondary absorber. If for any reason it is found desirable to keep the solution from boiling, the water can be delivered at a lower temperature. This may 30 at times involve cooling the water, for which purpose the water may pass through a suitable cooling tower or other cooling apparatus F'' before reaching the absorber. The acid solution which collects at the bottom 35 of the absorber may also be cooled, if desired, in any convenient way; as for example by its flow through the coil G' in the vessel G'' through which cold water is circulated. The water-seal H of course allows the acid-solution to pass freely out but prevents the 40 entrance of air.

The non-condensable gases, and any other gases and vapors that are not condensed or absorbed in the primary absorber, pass to the secondary absorber and there encounter a 45 descending stream of a solution of sodium carbonate or other suitable alkaline solution. Here the acid vapors present react with the base of the solution, and the liquid passes out through a liquid-seal into the tank K, whence it is delivered to the supply pipe J 50 by means of a pump indicated diagrammatically at L; old solution being withdrawn from and fresh solution added to that in the tank continuously or intermittently at a suitable rate. The precipitated fluorid also collects in the tank and is removed continuously or intermittently as may be desired, by any convenient means not shown. If a soda 55 solution is used the precipitate is sodium fluorid, which may be used in the manufacture of cryolite or other double fluorid of sodium or aluminum. The gaseous residue passes out of the absorber B at the top thereof, through a suitable exhauster M, and is 60 discharged from a stack not shown; the ex-

hauster serving to create the vacuum, in the absorbers and in the acid-vapor generator or still, which produces the flow of vapors and gases from the generator through the absorbers. A considerable part of the vapors 70 admitted to the secondary absorber is condensed therein by passing upwardly through the descending stream of alkaline liquid. It may at times happen, however, that the vapors carry so much heat into the secondary 75 absorber (particularly if the solution in the primary absorber is boiling) that the solution in the secondary becomes too hot, with the result that condensation of the vapor is diminished and too much vapor passes out 80 through the exhauster. In such case the solution can be cooled in any convenient manner, as by means of a cooling tower K'', through which the liquid flows on its way to the top of the absorber. As the solution is 85 circulated through the absorber more and more of its carbonate is removed by reaction with the hydrofluoric acid. Accordingly the absorber is replenished from time to time by dissolving fresh carbonate in the liquid in 90 the tank K, or fresh solution is added, or both.

From the foregoing it will be seen that the process is continuous, the acid vapors being 95 continuously drawn from the still and through the absorbers, and the waste or solid residue from the still is continuously discharged through the water seal 33. The economy thus secured has in practice been found to be very great. Another important 100 advantage flows from the fact that the operations take place in a partial vacuum, so that there can be no escape of corrosive fumes into the air adjacent to the apparatus. It is thus possible for the workman to open 105 the still, as often as desired, for the purpose of supplying raw material thereto, without suffering injury or even inconvenience or discomfort. This contributes to the well-being of the workmen and hence makes them 110 more efficient, thereby contributing, though indirectly, to the economy of the process. The process also possesses another important advantage, which can be described as follows. In the manufacture of aluminum 115 fluorid, or cryolite, it has been found exceedingly difficult to precipitate the fluorids completely from the solution resulting when hydrofluoric acid is neutralized with aluminum hydrate, sodium hydrate, or other materials containing alumina or soda. If dilute 120 solutions of fluorids, resulting from the manufacture of aluminum fluorid or cryolite, are returned to condensers of the prior types, in which the hydrofluoric acid-vapors 125 are passed through the water solution in the tank, a precipitate is formed which clogs the vapor pipes and renders the operation of the still dangerous. In the present invention the vapors do not pass through a body of liquid 130

in a tank but through a stream of water or solution, and any precipitate formed is washed down, and off the baffles, by the continuous stream and passes out through the 5 water seal at the bottom.

It is to be understood that the invention is not limited to the particular apparatus herein described, but can be practised by other means without departing from its 10 spirit.

I claim:

1. The herein described continuous process of producing fluorids and hydrofluoric acid, which consists in continuously generating hydrofluoric acid gas in a closed chamber or retort, applying suction to the retort and drawing the acid gas through a stream of absorbing liquid flowing through a closed absorbing chamber, drawing unabsorbed gas 15 from the latter chamber and through a stream of liquid flowing through a second closed absorbing chamber and containing in solution a compound capable of reacting with the hydrofluoric acid and producing a 20 fluorid, and collecting the acid solution from the first absorbing chamber and the fluorid from the second, the generation, and absorption reaction all taking place under pressure less than atmospheric.
2. The herein described continuous process of producing hydrofluoric acid and salts thereof, which consists in continuously generating hydrofluoric acid gas in a closed retort, applying suction to the retort and 25 drawing the acid gas therefrom upwardly through a closed absorber and through a stream of absorbing liquid descending therein, drawing unabsorbed gas by suction from the top of the absorber and upwardly 30 through a second closed absorber through which is descending a stream of liquid containing in solution a compound to react with the acid gas and produce the desired fluorid, while withdrawing liquid from the bottom 35 of the second-named absorber and delivering it into the top thereof, collecting acid-laden liquid from the bottom of the first absorber and fluorid from the bottom of the second, and from time to time replenishing 40 the second absorber, the generation, absorptions and reactions taking place under pressure less than atmospheric.
3. The herein described continuous process of producing hydrofluoric acid and salt 45 thereof, which comprises continuously generating gases containing hydrofluoric acid under pressure less than atmospheric, drawing the acid gases against a counter current of downwardly flowing sub-divided, agitated, absorbing liquid, while said gases are still under pressure less than atmospheric, whereby the gases are caused to pass through the falling liquid, drawing the unabsorbed gases by suction upwardly against 50 a counter current of an agitated, sub-di-

vided, absorbing liquid containing a compound capable of reacting with the hydrofluoric acid gas and producing therewith a fluorid, collecting the acid-laden liquid from the first absorption step, and the fluorid 70 from the second absorption step and from time to time replenishing the second absorbent liquid.

4. The herein described continuous method for the purpose described, which consists in 75 continuously generating hydrofluoric acid gas in a closed chamber, applying suction to the closed chamber to draw the acid gas therefrom, drawing the acid gas by suction upwardly through a closed absorbing chamber and simultaneously delivering an absorbing liquid to the top of the absorbing chamber whereby the gas is caused to pass through a descending stream of the liquid, and collecting the liquid at the bottom of 80 the absorbing chamber, the generation and absorption of the acid gas taking place under a pressure less than atmospheric.

5. The herein described method which 85 comprises the successive steps of (a) generating hydrofluoric acid, (b) absorbing a portion of the hydrofluoric acid in water, (c) absorbing at least a portion of the remaining hydrofluoric acid in a liquid containing a base, all three of these operations 90 being formed under pressure lower than atmospheric.

6. The herein described process for the purpose described, which consists in 95 continuously generating hydrofluoric acid gas 100 in a closed retort under pressure less than atmospheric whereby the retort may be opened from time to time for the introduction of acid-producing materials without the escape of gas, drawing the acid gas by suction from the retort and through a closed absorbing chamber, passing a stream of absorbing liquid through the chamber in the opposite direction to the flow of gas, at a rate and initial temperature adapted to 105 cause boiling of the liquid by the heat of absorption, and collecting the acid-laden liquid at the bottom of the chamber.

7. The herein described process, comprising 110 drawing hydrofluoric acid gas by suction through a closed absorber, passing through the absorber a solution containing a reagent to react with the acid gas for the production of a fluorid, returning the solution to the absorber repeatedly, and removing 115 fluorid therefrom.

8. The herein described process which 120 comprises treating gases containing hydrofluoric acid, in the form of an upwardly flowing stream of said gases, with an absorbent liquor containing a reagent capable of reacting with the said acid to produce a fluorid, while agitating and sub-dividing the said liquor.

9. The herein described process which 125

comprises drawing gases containing hydro-fluoric acid upwardly in contact with a downwardly flowing, agitated and sub-di-
5 vided absorbent liquid containing an alkali in solution, while maintaining said gases, under pressure less than atmospheric, and circulating the absorbent liquid.

10. In the production of hydrofluoric acid solution, the improvement which com-
10 prises bringing a current of hydrofluoric

acid gas into contact with a counter flowing current of water, under pressure below atmospheric, while so regulating the amount and temperature of the water relative to the amount and temperature of the hydro- 15 fluoric acid gas, as to produce a substantially boiling hydrofluoric acid solution.

In testimony whereof I hereunto affix my signature.

RALPH S. SHERWIN.
